[57] **ABSTRACT**

Printing means for high-speed non-impact printers of the type having character-shaped, pulsed electrodes. Mutually facing electrode and terminal sheets have insulating bases upon the nonfacing surfaces of which are disposed character electrodes and corresponding connection terminals. The respective electrodes and terminals are mutually connected by conductor leads extending through the sheets. Surrounding portions of the non-facing surfaces and portions of the facing surfaces extend about the electrodes and terminals and are electrically conductive and connectable to circuit means for the purpose of shielding and suppressing arcs between electrodes or between terminals, or between electrodes and terminals.

ELECTRODE AND TERMINAL STRUCTURE FOR NON-IMPACT PRINTER

BRIEF SUMMARY OF THE INVENTION

This invention relates generally to printers effective by means of pulsed, character-shaped electrical fields in the region of the printing surface. Examples of such printers are disclosed in the U.S. Pat. to Robert W. Haeberle et al. U.S. Pat. No. 3,550,153, dated Dec. 22, 1970. This patent describes printing by means of a pulse of short duration creating a shaped electrical field between a donor sheet and a closely adjacent recipient sheet. The surface of the donor sheet facing the recipient sheet carries electrically conductive particles of a printing material or pigment dispersed in or on a high resistance medium. The electrical field causes a current flow that leaves a sufficient charge on the printing material to cause it to move to the recipient sheet under the influence of the shaped electrical field. The electrical pulses are typically of very brief duration and are applied between a first, character-shaped electrode and a second or "ground" electrode so disposed that the donor and recipient sheets are within the shaped electrical field. The amplitude of the applied pulses depends on a number of factors including the construction and orientation of the sheets and the presence or absence of intervening insulator sheets, but typical values may range from several hundreds of volts to more than 1,000 volts.

In typical alphanumeric printers it is desirable and usually necessary to locate the character-shaped electrodes in close physical relationship. This presents a problem of possible arcing between the electrodes whereby defective printing as well as spurious printing of undesired characters may result. An object of this invention is to provide printing means adapted to prevent such arcing, whereby the full pulse for each desired character to be printed is delivered only to the appropriate electrode.

Another object is to provide printing means having a compact, simplified and economically fabricated structure.

This invention achieves the foregoing objects, as well as other objects hereinafter appearing, by the provision of a pair of mutually facing sheets respectively having upon their nonfacing surfaces the character-shaped electrodes and the corresponding terminals for connecting the electrodes with the pulse circuits of the printer. The sheets are electrically connected by a number of leads that extend through insulating substrates on the sheets and respectively connect each electrode with its corresponding terminal. Portions of the sheets adjacent to and surrounding the electrodes and terminals are grounded for arc suppression and shielding purposes.

Other features of the invention will be evident from the following description of a preferred embodiment thereof.

BRIEF DESCRIPTION OF THE DRAWING

FIG. 1 is a view in plan illustrating the principal parts of a high speed non-impact, pulsed electrode printer embodying this invention.

FIG. 2 is a front elevation taken on line 2—2 of FIG. 1.

FIG. 3 is a side elevation in section taken on line 3—3 of FIG. 2.

FIG. 4 is an exploded view showing the structures of the electrode and terminal sheets.

DETAILED DESCRIPTION

Referring to the drawing, the printing means according to this invention comprises an electrode sheet 12 and a terminal sheet 14 in closely adjacent, facing relationship, the sheets being mounted upon an arcuate support 16. Extending from the support 16 is a cable 18 containing a plurality of wires 19 leading to character selection control circuits for the printer. These circuits may take various forms within the purview of one skilled in this art, as will be evident from the description below.

A composite paper web 20 extends from a supply roll 22 over a curved face of the electrode sheet 12 to a take-up roll 24. These rolls are driven in a conventional manner, preferably at a constant speed bearing a predetermined relationship to controls for the character selection impulses passing through the several wires 19. A flexible metal band 28 is received over rolls 30 and held under tension by a spring 32, thereby urging the web 20 with a light pressure against the surface of the sheet 12. Preferably, the band 28 is grounded to the frame of the printer, as illustrated.

The paper web 20 may be of any suitable type adapted to form a visible or latent image of selected characters when subjected to an electrical field formed by the application of brief electrical pulses between the electrode sheet 12 and the band 28. While the invention is not primarily concerned with the particular structure of the web 20, an example is illustrated in the drawing for application of the invention to the methods described in the above-identified Haeberle patent. This web comprises a donor web 34 and a recipient web 36. The donor web 34 may comprise a substrate fabric of cloth material, paper or plastic film, which either comprises or has coated upon it a high resistivity medium upon which printing particles 38 are dispersed. These particles are mobile and electrically conductive pigment particles which, in the presence of a brief electrical field pulse, are physically transferred from the donor sheet to the facing surface of the recipient web 36 as described in said patent. The web 36 may be any suitable paper upon which the particles may be thus deposited to form a visible image. The shape of this image depends upon the shape of the applied electrical field which is defined by the shapes of character electrodes on the sheet 12 as hereinafter described. While the webs 34 and 36 are shown in FIG. 3 as being somewhat separated, in practice they are preferably in facing contact, being held in contact by a light pressure applied by the band 28 or by other means that will permit easy and rapid separation of the webs 34 and 36 after the image transfer has occurred.

Details of the structure of the electrode and terminal sheets 12 and 14 are illustrated in FIGS. 3 and 4. Preferably, the sheets both have the same basic structure consisting of insulating bases or substrates 40 and 42 of high dielectric material such as nylon or the equivalent, these substrates being initially coated with a layer of copper or other metallic conductor. Both surfaces of the sheet 14 are so coated, and the non-facing surface of the sheet 12 is thus coated. The copper is selectively etched from the surfaces to leave the residual conductive patterns as hereinafter more fully described.

The side of the electrode sheet 12 that faces the composite web 20 has a large electrically conductive marginal surface 44 defining a central etched region 46 that is non-conductive except for a pattern of electrically conductive character-shaped electrodes 48, preferably arranged in a line containing all of the available alphanumeric characters and any other desired punctuation marks, patterns, designs including logotypes, ligatures and symbols to be printed in desired sequences to form a text, music or other composition, or a formula or any other visible collocation of the available characters. The opposite face of the sheet 12 is preferably uncoated whereby the insulating surface of the base 40 is exposed throughout the area of the sheet 12 facing the sheet 14.

The electrode sheet 14 has a side 50 facing the sheet 12, this side having a substantial electrically conductive marginal surface 52 defining an etched, non-conductive central region 54 generally aligned with the region 46 on the sheet 12, and also defining non-conductive margins 55. The sheet 14 also has a side 56, this side having a substantial electrically conductive marginal surface 58 and a plurality of mutually spaced electrically conductive strips 60. These strips, like all of the other electrically conductive surfaces on the sheets 12 and 14, are preferably formed by acid-etching of copper or other metallic coatings in accordance with well-known techniques, but any other suitable method of providing conductive surfaces may be employed.

The strips 60 preferably have eye-shaped central end portions 62 and terminal end portions 64. The central portions 62 are located in opposed relationship to the non-conducting, uncoated central region 54 on the opposite side of the sheet 14, and the end portions 64 are preferably located near the side periphery of the sheet 14 in opposed relationship to the non-conductive margins 55. Substantial spacing exists between the respective ends 64 to facilitate connection with external control circuits. For making such connections, holes 66 are preferably drilled through the sheet 14 in the centers of the eye-shaped ends 62 and 64 of the strips 60, and connection wires such as 67 are soldered to the end terminals 64 and extend to the pulse circuits associated with the wires 19.

An electrical lead wire 68 passes through a drill hole in the base 40 of the sheet 12 (FIG. 3) and is soldered or otherwise electrically connected with the underside of each character electrode 48. This wire passes through a corresponding hole 66 in the sheet 14 and is soldered as at 70 to a central end portion 62 of a corresponding strip 60. Thus the opposite terminal end portion 64 of this strip comprises terminal means by which the character may be connected through the wire 67 with circuits associated with the leads 19 of FIG. 1.

The above-described structure also provides means for shielding the respective character electrodes 48 and strips 60 from one another and from spurious externally-generated electrical fields. To this end, those electrically conductive surface portions of the sheets 12 and 14 that are not electrically connected with the electrodes 48 and strips 60 as above described are connected together and suitably grounded to the control circuit. This may be accomplished in various ways, for example by machine screws or other fasteners passing through holes 72 that also serve for alignment and support of the sheets. Thus the surface portions 44, 52 and 58 are electrically connected together and grounded.

The shielding between each adjacent pair of strips 60 is further increased by the provision of integral spaced extensions 74 of the surface 58, as shown in FIG. 4. By this means the surface portion 58 electrically isolates the respective strips 60. Preferably, the strips 60 are often arranged so that alternate strips extend in opposite directions from the central portion of the sheet 14 as shown, thereby providing space for the extensions 74 as above described.

In a corresponding manner, longitudinally-extending electrically conductive lateral portions 76 of the surface 52 between the non-conductive areas 54 and 55 provide isolation between circuit wires such as 67 and the leads 68 extending between the sheets 12 and 14.

15 Printing means comprising sheets 12 and 14 are readily fabricated in the manner hereinabove described, and a given printer may be provided with a large number of pairs of sheets comprising various typographical styles and combinations of selectable printing characters 48. Etching techniques employing photographic resists, which are well known in the art, are easily adapted to the production of these sheets.

20 It will be understood that this invention is concerned primarily with certain structural aspects of the printing sheet means as hereinabove described, and that it may be employed upon sheets having other than a single rectilinear array of characters thereon. It is possible, for example, to employ a plurality of rows of characters or to arrange them along a curve conforming to the path of the moving composite paper web 20, for example:

25 Other variants of the above-described structures will be apparent to one skilled in this art, in order to conform to selected printer configurations and printing circuit requirements.

We claim:

1. Printing means having, in combination, an electrode sheet comprising an insulating base and a plurality of character-shaped electrodes arranged in a pattern on a surface thereof, said surface having a conductive portion substantially surrounding the region including said pattern without electrically contacting said electrodes,

30 a terminal sheet having a surface facing the other surface of said electrode sheet and comprising an insulating base and a plurality of mutually spaced electrically conductive strips on the non-facing surface thereof, each strip corresponding to an electrode on the first sheet and having a first end and a second end, the first ends of said strips being aligned with said pattern and the second ends having terminal means,

35 and a lead extending through the bases of said sheets and electrically connecting each said electrode with the first end of a corresponding strip.

2. Printing means according to claim 1, wherein the electrodes are etched metallic coatings.

3. Printing means according to claim 1, wherein the electrodes and strips are etched metallic coatings.

4. Printing means having, in combination, an electrode sheet comprising an insulating base and a plurality of character-shaped electrodes arranged in a pattern on a surface thereof,

50 a terminal sheet having a surface facing the other surface of said electrode sheet and comprising an insulating base, a plurality of mutually spaced electrically conductive strips on the non-facing surface

thereof and mutually connected conductive portions extending between said strips, each strip corresponding to an electrode on the first sheet and having a first end and a second end, the first ends of said strips being aligned with said pattern and the second ends having terminal means, and a lead extending through the bases of said sheets and electrically connecting each said electrode with the first end of a corresponding strip.

5. Printing means according to claim 4, wherein the electrodes are etched metallic coatings.

6. Printing means according to claim 4, wherein the electrodes and strips are etched metallic coatings.

7. Printing means according to claim 4, wherein said

strips are generally parallel and said conductive portions are elongate and extend between said strips.

8. Printing means according to claim 7, wherein said facing surface of said terminal sheet has a conductive portion extending transversely of said strips between and in nonoverlapping relation to the first and second ends thereof.

9. Printing means according to claim 7, wherein said pattern is substantially linear and said strips extend transversely thereof.

10. Printing means according to claim 9, wherein adjacent strips extend on alternate sides of said pattern.
